UNITED STATES PATENT OFFICE

166,334

COMBINED BIRD PERCH AND MIRROR

Lester Moon, Chicago, Ill.

Application May 1, 1951, Serial No. 15,037

Term of patent 7 years

(Cl. D31—2)

To all whom it may concern:

Be it known that I, Lester Moon, a citizen of the United States, residing at Chicago, in the county of Cook, State of Illinois, have invented a new, original, and ornamental Design for a Combined Bird Perch and Mirror, of which the following is a specification, reference being had to the accompanying drawing, forming a part thereof.

Fig. 1 is a top plan view of a combined bird perch and mirror showing my new design. Fig. 2 is a front elevational view thereof; and Fig. 3 is a side elevational view thereof.

I claim:

The ornamental design for a combined bird perch and mirror, as shown.

LESTER MOON.
